UNITED STATES PATENT OFFICE.

HENRY NYBERG, OF CHICAGO, ILLINOIS.

AIR-PUMP.

No. 859,408.

Specification of Letters Patent.

Patented July 9, 1907.

Application filed March 20, 1905. Serial No. 251,043.

To all whom it may concern:

Be it known that I, HENRY NYBERG, a citizen of the United States of America, and a resident of Chicago, in the county of Cook and State of Illinois, have invented 5 certain new and useful Improvements in Air-Pumps, of which the following is a specification.

The main objects of my invention are to provide an improved form of air pump, which shall be simple, compact, light, efficient and particularly adapted for 10 inflating the pneumatic tires of automobiles; to provide simple means for readily connecting the same with the driving mechanism of the vehicle; and to provide an improved form of casing adapted to protect from dust and dirt, the driving mechanism of the pump.

15 I accomplish these objects by the device shown in the accompanying drawings, in which:

Figure 1 is a side elevation of an automobile air pump constructed according to my invention. Fig. 2 is a longitudinal section through the cylinders of the pump 20 on the line 2—2 of Fig. 1. Fig. 3 is a transverse section of one of the cylinders on the line 3—3 of Fig. 2. Fig. 4 is a section of Fig. 2 on the line 4—4.

In the construction shown in the drawings, the main frame of the pump consists of a casing 4 which is formed 25 of two sections rigidly connected together by flanges 5, the joint being in a plane extending transversely through the crank chamber 7. Each half of the casing is provided with a cylinder 6 opening toward the crank chamber. Said cylinders are in axial alinement with 30 each other and each is provided with a piston 8. The pistons are rigidly connected together by the piston rod 9 which is preferably integral therewith and extends between the pistons at one side of the axial line of the cylinders. A crank plate 10 is mounted on the shaft 11, 35 which is journaled in one side of the casing 4 on an axis intersecting the axis of the cylinders and at right angles thereto. The plate 10 is provided with a crank pin 12 which is connected by means of a pitman 13 with one of the pistons 8. The said piston is cored out to 40 form a central recess 14 for receiving the end of the pitman, which is secured in position by the wrist pin 15 extending transversely through the piston. The wrist pin is secured against shifting endwise by the piston rings 16, which are seated in an annular groove in the 45 piston in the usual manner. The plate 10 is provided on the face, which is opposite to the crank pin, with a concentric internal gear 17. Rotation is imparted to the plate 10 by means of a pinion 18 which meshes with the gear 17, as indicated by the dotted pitch circles in 50 Fig. 1. The shaft of the pinion 18 extends through the casing at one side of the shaft 11 and carries at its outer end a pulley 19 which has a suitable friction surface 20 on its periphery for engaging the fly wheel of the engine and utilizing power therefrom. The plane of the 55 joint between the parts of the casing 4 preferably coincides with the plane of the shaft 11 and the shaft of the

pinion 18, so that said shafts may be readily removed without disturbing the connection of the gears and their shafts.

Each cylinder is provided at its outer end with a passage 21 communicating with a valve chest 22. These valve chests contain the air inlet and outlet valves. The air inlet openings are preferably in the ends of the valve chests and are therefore not shown in the drawings. The air outlets are each connected by piping 23 65 with an oil separator 24, to which is attached a flexible tube which should be of sufficient length to connect with the air valves of any of the tires of the vehicle. The piping 23 is provided with a union 25 for permitting the ready separation of the parts of the casing. 70

One end of the casing is pivoted at 26 to a bracket 27 which is rigidly secured to a part 28 of the supporting framework of the vehicle. The other end of the casing 4 is connected by means of a pair of toggle links 29 with a pin 30, also rigidly secured to some adjacent part of 75 the supporting frame, in suitable position to bring the periphery of the pulley 19 adjacent to the periphery of the fly wheel of the engine. The said fly wheel is indicated at 31 in the drawings. The spring 32 connects the casing with the supporting framework and normally urges the pulley 20 into frictional contact with the fly wheel 31. The position of the toggle links is controlled by means of a rod 33. The full lines in Fig. 1 show the toggle links in their collapsed position, as when the pump is being operated. When the pivot 34 80 is moved to the position indicated by the dotted lines 34', the lugs 35 will prevent further bending of the toggle joint in an upward direction and the spring 32 will then serve to prevent collapsing of the toggle joint and thus hold the pulley 19 out of contact with the fly 90 wheel 31, until the rod 33 is pulled in a downward direction.

The oil separators 24 consist of a hollow casing having 95 inlet and outlet passages and having interposed between said passages a plurality of curved deflectors or partitions 36. These break the direct flow of the air and cause any oil which is carried by the air to be deposited on adjacent walls. This oil flows to the bottom of the casing and is removed by a blow off cock 37.

The operation of the mechanism of the pump will be 100 readily understood from the foregoing description.

It will be noted that all of the gearing and pitman mechanism is inclosed by the casing and is at the same time readily accessible through the separability of the parts of the casing and all of the working parts are assembled in compact form between the adjacent ends of the cylinders. The pistons are rigidly connected together in such manner that one makes its suction stroke while the other is discharging. The pull of the frictional contact between the pulley and fly wheel is increased to give the desired air pressure in the cylinder by the gearing. The pump is started or stopped by 110

merely shifting the rod 33, the toggle and spring mechanism being self locking in either position. Any lubricating oil which is carried out of the cylinders by the air is removed at the separator 24 and can therefore 5 cause no injury to the tires.

It will be seen that numerous details of the construction shown may be altered without departing from the spirit of my invention.

What I claim as my invention and desire to secure by 10 Letters Patent, is:-

1. In a device of the class described, the combination of a frame, a pair of opposed cylinders mounted in said frame in axial alignment and each open toward the other, pistons slidable in said cylinders, a piston rod rigidly 15 connecting said pistons together and extending between the same at one side of the axes of said cylinders, a crank journaled within the casing and between the pistons, a pitman connecting said crank and pistons, and a driving shaft having thereon within the casing, a 20 pinion geared to said crank.

2. In a device of the class described, the combination of a frame, a pair of opposed cylinders mounted in said frame in axial alignment and each open toward the other, pistons slidable in said cylinders, a piston rod rigidly

connecting said pistons together and extending between 25 the same at one side of the axes of said cylinders, an internal gear wheel journaled within the casing between the pistons, a pitman connecting said internal gear wheel and pistons, and a driving shaft extending into the casing and having a pinion meshing with said internal 30 gear wheel.

3. The combination of a frame, a wheel journaled therein, a closed casing pivotally mounted at one end near said wheel, pumping mechanism in said casing, a friction pulley journaled on said casing and adapted to 35 operate said pumping mechanism, said friction pulley being movable into and out of engagement with said wheel through the rocking of said casing on its pivotal axis, a toggle link pivotally connected to said casing, a second toggle link pivotally connected to the first and to 40 said frame, a tension spring connecting the opposite ends of said links, and normally urging the pulley into frictional contact with said wheel, and a rod connecting the joint between said toggle links and extending substantially at right angles to the line of said links for operating 45 the toggle joint, substantially as described.

Signed at Chicago this 25 day of Jan. 1905.

HENRY NYBERG.
